UNITED STATES PATENT OFFICE.

FREDRICH DOMBROWSKI AND JACOB WOLTMANN, OF ST. LOUIS, MISSOURI.

LASTING-MACHINE.

SPECIFICATION forming part of Letters Patent No. 337,752, dated March 9, 1886.

Application filed October 23, 1885. Serial No. 180,750. (No model.)

To all whom it may concern:

Be it known that we, FREDRICH DOMBROWSKI and JACOB WOLTMANN, of St. Louis, Missouri, have jointly made a new and useful Improvement in Shoe-Lasting Machines, of which the following is a full, clear, and exact description.

The improvement relates more especially to the construction of the jack; to the means for drawing the upper onto the last, and for closing it over upon the insole; to the means for adjusting the last to the movement of the gripping device as the upper is closed upon the insole; to the means for holding the upper in place after it has been drawn onto the last and closed upon the insole, and to the means for applying the upper to the insole.

The annexed drawings, making part of this specification, exhibit the improved construction.

Figure 1 is a side elevation of the machine. Fig. 2 is a front elevation of the machine. Fig. 3 is a horizontal section on the line 3 3 of Fig. 1. Fig. 4 is a horizontal section on the line 4 4 of Fig. 1. Fig. 5 is a view in perspective of one of the grippers, being the one used at the toe of the shoe. Fig. 6 is a horizontal section on the line 6 6 of Fig. 1. Fig. 7 is a similar section, the clamp being opened. Fig. 8 is a horizontal section on the line 8 8 of Fig. 1. Fig. 9 is a horizontal section on the line 9 9 of Fig. 1. Fig. 10 is a side elevation showing the grippers applied to the upper. Figs. 11 and 12 are sectional views on the line 11 12 of Fig. 10, and respectively of a right and left shoe. Fig. 13 is a similar section, but showing the grippers closed toward each other and the upper edges drawn downward upon the insole. Figs. 14 and 15 are views corresponding, respectively, to Figs. 11 and 12, and showing the clamp bearing upon the upper edges. Fig. 16 shows the nail-holder resting upon the upper and supporting the nails in position for nailing. Figs. 17 and 18 are views illustrating the method of driving the nails. Fig. 19 shows the upper nailed to the insole. Figs. 20 and 21 are respectively a plan and a side elevation, partly in section, of the nail-holder; and Figs. 22 and 23 are respectively a plan and a side elevation of the punch used to introduce the nails.

The same letters of reference denote the same parts.

The last A, Figs. 1, 2, having the upper (not shown in the figures named) attached, is placed in position upon the jack B and moved into position for the upper to be acted upon by the mechanism for stretching it upon the last.

The jack consists, mainly, as follows: a heel-support, b, a toe-support, b', a plate, b², upon which the supports b b' are more immediately placed, a sub-plate, b³, and guide-pins b⁴, which extend from the plate b² downward through the sub-plate b³, and a screw, b⁵, which supports the plate b² and in turn is held and adapted to be worked upward and downward in a block, b⁶, that is held in the sub-plate b³. The heel-support b is jointed at b⁷ to a bearing, b⁸, upon the plate b², and by means of the wedge b⁹, which is pivoted at b¹⁰ to the plate b², the heel-support can be turned upon its bearing toward and from the toe-support, and thereby adjust the last with relation to the toe-support and clamp and unclamp the last, as may be desired. The toe-support can be adjusted upon the plate b² toward and from the heel-support by means of the screw b¹¹, which is held in the standard C and works through the toe-support. In this manner provision is made for longer or shorter lasts. By means of the screw b⁵ the plate b² and the parts thereupon can be raised and lowered to a limited extent for the purpose of adjusting the last more accurately in a vertical direction. The pins b⁴ guide the plate b² in the movement last described.

The jack as an entirety is adapted to be moved toward and from the standard C by adapting the sub-plate b³ to be held and moved in a base-plate, D.

To receive the last the jack is drawn out upon the base-plate into the position shown in the full lines in Fig. 8, and after the last has been secured the jack is slid inward upon the base-plate into the position indicated by the dotted lines, Fig. 8, and the full lines in Fig. 1. The base-plate D is attached to some fixed part of the machine, such as the arm E, which also supports the gripping mechanism and clamping mechanism, which will now be described.

The mechanism for gripping the upper F, Figs. 10, 11, 12, and drawing it upward upon the last and afterward closing its upper edge over upon the insole, G, consists, mainly, first, of the grippers H, Figs. 1, 2, 4, 5, which are adapted to lay hold of the upper; second, a head, h, to which the grippers are attached, and which is adapted to be raised and lowered in the arm E, and thereby to draw the grippers upward and lower them downward, as desired; and, third, a guide, I, which can be made to coact with the grippers and cause them to be moved horizontally, and thereby enable the edge of the upper to be drawn over upon the insole. A series of the grippers H is employed in order that the upper may be taken hold of along the sides and at the toe of the last. The grippers are generally similar, but may be varied slightly to accord with their respective positions around the last—that is, they all have some appliance, such as the jaw h', pivoted at h' to the main arm h' of the gripper and adapted by means of a spring, h', to press against the main-arm jaw h'', and thereby nip the upper; but, as shown in Fig. 5, the jaws h' h'' are in the case of the gripper used at the toe of the last shaped to suit the upper and last at that point. The grippers, by means of the lever h'', which is pivoted at h'' to the arm E and jointed at h' to the part h' of the head h, are lowered to bring the grippers into engagement with the upper, after which the grippers are, carrying the upper F, drawn upward until the edge f of the upper is drawn upward sufficiently to be turned over upon the insole. The operator then, by placing his foot on the treadle J, which is journaled at j and jointed to the standard C, raises the guide I, which, when raised, encounters the inclined portion h¹⁰ of the gripper-arms h', and thereby causes the arms to be swung inward on the pivots h¹¹, and the grippers and upper to be moved from the position of Fig. 11 into the position of Fig. 13, after which the upper is clamped to the last by means of the clamp K. This last-named part is shown more distinctly in Figs. 1, 6, 7. Two arms, k k, are hinged together around the standard C, and are adapted to be moved as indicated by the two positions shown, respectively, in Figs. 6, 7. They are similarly furnished with a plate, k', whose edge k'' conforms to the side of the last opposed to it. By closing the arms k k and securing them as by means of the catch k³ the plates k' k'' are brought to bear upon the upper, as shown in Figs. 14, 15, so as to clamp it upon the last and insole. The grippers can now be withdrawn upward from their hold upon the upper, and the nail-
ing mechanism brought into use.

65 L represents a part which may be styled the "nail-holder." It is essentially a plate shaped to conform to the last, so that after the grippers are out of the way it can be laid upon the last, insole, and upper, as shown in Figs. 16, 17, 18. The holder L has a series of holes, l,

passing vertically through it for receiving and bolting the nails t . A punch, M, Figs. 22, 23, provided with the points m , which in number and position correspond with the holes l , is then placed over the nail holder h to bring the points m upon the nails t . Then by striking the punch downward the nails are driven into the upper and insole, substantially as indicated in Fig. 18, and completing the operation, substantially as shown in Fig. 19. 75

In raising the guide I to effect the moving of the grippers inward over the last, as described, provision must be made for accommodating the last to the movement, as otherwise the upper might be unduly strained. To this end the standard C is provided with a tappet, c, which, when the standard is raised, lifts the bearings c' c', which are respectively in the base-plate D and the bracket e, encountering a tappet, b', upon the block b², FIG. 2, and thereby causes the jack supporting the last to be lifted sufficiently to suit the inward movement of the grippers.

The blocks h^1 , Figs. 2, 3, to which the gripper arms h^2 are pivoted, are, by means of the screws h^3 and the cross-bars h^4 , (which can be slipped sidewise on the head h and are shown to receive the blocks h^1 , substantially as shown,) moved nearer together or farther apart from each other in the head h , and the gripper arms thereby relatively adjusted at their upper ends. The gripper arms h^2 are toward their lower ends, and by means of the screws h^5 , the slotted cross-bars h^6 , and blocks h^7 , Fig. 4, are made suitably adjustable.

We claim—

1. In a shoe-lasting machine substantially as described, the combination of the pivoted heel-support b , the adjustable toe-support b' , the plate b' , the wedge b'' , the screw b''' , and the standard C, substantially as described.
  2. In a shoe-lasting machine substantially as described, the combination of the plate b' , carrying a heel and a toe support, the screw b'' , and the base-plate D, substantially as described.
  3. In a shoe-lasting machine substantially as described, the combination of the plate b' , carrying a laterally-adjustable heel support, the plate b' , the base-plate D, the screw b'' , and the guide-pins b''' , substantially as and for the purposes set forth.
  4. In a shoe-lasting machine substantially as described, the combination of the plate b' , carrying an adjustable heel and a toe support, the screw b'' , the block b''' , the base D, and the plate b''' , movable thereon, substantially as described.
  5. In a shoe-lasting machine, the combination of the plate b' , the toe-support b , the pivoted heel-support b , and the pivoted wedge b'' , and means, substantially as described, for supporting the same, all as set forth.
  6. The combination, in a shoe-lasting machine, of the arm E, the grippers H, upward by said arm and pivoted by means, substantially as described.

tially as described, to be swung over the last, the guide I, the standard C, and treadle J, substantially as described.

7. The combination of the treadle J, the standard C, the tappets $c b^{12}$, the jack B, and the pivoted grippers H, provided with supporting mechanism, substantially as described.

8. In a shoe-lasting machine substantially as described, the combination of the jack B, constructed and operating as set forth, the clamp K, and the grippers H, as and for the purposes described.

9. The combination, in a shoe-lasting machine, of the jack B, the clamp K, and the grippers H, with the guide I, provided with supporting mechanism to hold it in operative relation with the other parts, substantially as set forth.

10. In a shoe-lasting machine substantially as described, the clamp K, consisting of arms $k k$, hinged around the standard C, and provided with the plates $k' k'$, having the edges $k^2 k^2$, in combination with the standard E, all as and for the purposes described.

11. In a shoe-lasting machine, the combination of the jack B, as described, the clamp K, the nail-holder L, and the punch M, substantially as and for the purposes set forth.

Witness our hands.

FREDRICH DOMBROWSKI.
